ABSTRACT: A tubular heat exchange apparatus for use with two fluids, comprising, within a gas-tight casing, a plurality of tubes and two headers, said tubes being connected with such headers. The tubes are arranged in one or more rows or ranges around a central duct of variable cross section. The heat exchange apparatus is adapted to convey combustion gases from a furnace or the like.

TUBULAR HEAT EXCHANGE ASSEMBLY

BACKGROUND OF THE INVENTION

The present invention relates to an improved tubular heat exchange assembly for use with two fluids, such as liquids, vapours and/or gases, and is of the type comprising, within a gas-tight casing a plurality of tubes operably connected with two headers, one of the fluids flowing through the tubes and the other one outside and along them.

In the heat exchange assembly according to the invention, tubes of straight or curved shape are arranged so as to provide between them a central channel for the fluid flowing outside the tubes.

When that channel is narrow, the heat transmission is obviously effected essentially by convection. In heat exchange assemblies designed for increased heat transmission by radiation, that channel is widened into a radiation chamber of vertical, horizontal or inclined position, hereinafter referred to as a duct. Around ducts of uniform cross section, the tubes defining their contour may be easily arranged at equal and constant intervals over their entire length. Around ducts of variable cross section, however, the regular arrangement of the tubes is complicated by the fact that, following the variation of the cross section, the spacing or intervals between the tubes cannot be kept constant over their entire length. Larger intervals will alternate with smaller ones and even with superposed tubes. That requires a great deal of skilled work for the fabrication and thus increased costs.

Another inconvenience lies in the fact that with the tubes arranged in an irregular way, as described above, the thermal load will be different for the various tubes or even for various parts of the same tube. With high gas velocities in chambers of intense radiation, close arrangements of the tubes may even hinder the free flow of the radiating fluid.

SUMMARY OF THE INVENTION

Accordingly, the present invention seeks to obviate these inconveniences.

To accomplish this objective, the invention provides a heat exchange assembly, more specifically for heat transmission by radiation, comprising tubes with both ends connected to respective headers, said tubes surrounding and defining a central duct of variable cross section for a heat transmitting fluid for instance.

A particular aspect of the invention is that in a heat exchange assembly as described above, and with tubes regularly arranged side-by-side, close fitting over their entire length, one of the tubes' parameters, i.e. the direction of the axis or the shape of the cross section, is for all tubes and in any plane orthogonal to the duct's axis, a single and definite function of the size of the respective cross-sectional area of the duct.

A preferred embodiment of the heat exchange assembly according to the invention incorporates a vertical duct of variable cross section, delimited or bounded by helicoidal tubes of variable inclination.

A further preferential embodiment of the heat exchange assembly according to the invention may incorporate at least two rows or ranges of tubes which are coaxially arranged.

Still another preferential embodiment of the heat exchange assembly teaches a vertical duct of variable but circular cross section throughout, with tubes of equal length and shape.

A still further preferential embodiment of the heat exchange assembly according to the invention embodies a vertical duct shaped as a hyperboloid of revolution, with straight tubes lying within the surface of said hyperboloid.

Another feature relates to an improved process for the fabrication of a heat exchange assembly with a central duct of variable but circular cross section throughout, using tubes of equal length and shape, all tubes being connected in identical way and arrangement with the respective headers.

BRIEF DESCRIPTION OF THE DRAWINGS

The invention will be better understood, and objects other than those set forth above, will become apparent when consideration is given to the following detailed description thereof. Such description makes reference to the annexed drawings wherein:

FIG. 1 is a longitudinal section of a heat exchange assembly with helicoidal tubes of variable inclination;

10 FIG. 2 is a longitudinal sectional view of a heat exchange assembly as illustrated in FIG. 3, taken along the line II-II thereof, with tubes shaped in accordance with their respective distance from the duct's axis;

15 FIG. 3 is a transverse sectional view of a heat exchange assembly of the type illustrated in FIG. 2, and taken along the line III-III thereof;

FIG. 4 is a transverse sectional view of a heat exchange assembly as illustrated in FIG. 2, taken along the line IV-IV thereof;

20 FIG. 5 is an enlarged transverse sectional view of a heat exchange assembly as illustrated in FIG. 2, taken along the line V-V thereof;

FIG. 6 is a longitudinal sectional view of a heat exchange assembly with two rows or ranges of tubes which are coaxially arranged; and

25 FIG. 7 is a perspective representation of a hyperboloid-shaped heat exchange assembly provided with straight tubes.

DESCRIPTION OF THE PREFERRED EMBODIMENTS

30 Describing now the drawings, in FIG. 1 the heat exchange assembly depicted, by way of example, incorporates two headers 1 and 2 and a plurality of tubes 3 having their upper and lower ends connected with these two annular headers 1 and 2. The tubes 3 are located in close-fitting, side-by-side arrangement, to thus define a central duct 4 for one of the media involved in heat transmission, generally the heat transmitting medium. The circular cross section of this duct 4, which for convenience has been designated by reference numeral 4q, is 35 variable in size along the duct's axis A₄.

40 Water is fed into the lower header 1 and rises through the tubes 3, the latter acting as boiler-tubes. A mixture of hot water and steam is thereby produced in the tubes 3, collected in the upper header 2 and discharged therefrom. The openings and pipe connections provided for this purpose at both headers are not represented in FIG. 1, in order to simplify the drawings.

45 The heat exchange assembly, as illustrated in FIG. 1, which may be assumed to be mounted on top of a high-temperature furnace operating with molten slag, and wherein the stream of hot combustion gases issues from said furnace with a pronounced twist or spin, will flow upwards through the duct 4 of the heat exchange assembly. Small particles entrained by the gas-stream, e.g. droplets of molten slag, will be separated by increased centrifugal forces in the narrow part of the duct 4 and will flow back into the furnace along the smooth inner surface of the duct 4.

50 The tubes 3 are all of identical helicoidal shape, with the inclination angle α varying in dependence upon the size of the respective cross-sectional area 4q, said variable angle of inclination being such that the tubes 3 are maintained in close-fitting, side-by-side position over their whole length and that, at no place, will there occur any superposition of neighboring or contiguous tubes 3.

55 Thus, and with all tubes close-fitting to each other over their entire length, in any plane E orthogonal to the duct's axis A₄, the angle of inclination α of the axis A₃ of any tube 3 will depend solely upon the size of the respective cross-sectional area 4q, said angle of inclination α of the axis A₃ of any tube, thereby constituting a characteristic tube parameter.

60 In a more general aspect, with the tubes arranged with intervals between them, the inclination angle α of the helicoidal tubes 3 will be determined both by the size of the respective cross-sectional area 4q and by the desired spacing between

neighboring tubes. The inclination angle α will be greatest in the plane E of the smallest cross section $4q$, with tangent α possibly being infinite, so that in that plane, the tubes 3 may be arranged with their axes parallel with the duct's axis A_4 . This is visible in FIG. 1 in the lower part of the duct 4 designated Be, comprising the smallest cross-sectional area $4q$, where $\alpha=90^\circ$ and tangent $\alpha=\infty$. In contrast, in the plane E with the largest cross-sectional area $4q$, the inclination angle α will be smallest, as is the case in the upper plane marked Eg in FIG. 1.

Instead of having the tubes 3 arranged in close fit, i.e. without a spacing between them, as is the case in FIG. 1, any desired spacing between the tubes may be adopted, so that the arrangement represented in FIG. 1 may be considered as an extreme case, with the tube spacing or interval being equal to zero.

Similarly, instead of a duct 4 with circular cross sections $4q$, as represented in FIG. 1, any other shape, e.g. oval may be chosen for the cross sections. However, the circular form is to be preferred, since it allows all tubes 3 to be of equal length and curvature. Circular cross sections $4q$ are furthermore of advantage, since the thermal load is evenly distributed at all tubes, thereby avoiding thermal stresses within the heat exchange assembly.

Around the tubes 3 there is provided a gas-tight casing 5 which is accommodated to the longitudinal profile or shape of the duct 4. On their inner face, that is, the face actually bordering the duct 4, studs may be provided on these tubes 3 which then serve to retain or support a layer of refractory material in order to protect the tubes 3 against excessive thermal load in a manner well known in the art.

The type of heat exchange assembly shown and described in connection with FIG. 1, is a short and compact construction, quite able to resist thermal shocks owing to the elasticity of the helicoidal tubes.

In the embodiment of tubular heat exchange assembly depicted in FIG. 2, the two headers 1 and 2 are connected by means of a plurality of tubes 3' which serve to define a central duct 4', with circular cross sections $4q'$ of variable size along the duct's axis A_4' . The tubes 3' are curved in conformity with the longitudinal profile of the duct 4', with their axes (marked A_3') lying in planes E', passing through the duct's axis A_4' (cf. FIGS. 3 and 4). For any of the identical tubes 3', the shape and size of its cross section $3q'$ varies in dependence upon the respective distance S between said tube 3' and the duct's axis A_4' , the relationship being such that in spite of the variation of the duct's cross-sectional area $4q'$ the tubes remain in close-fitting, side-by-side position, i.e. without any free spacing or interval and that, furthermore, at no place of the duct 4', does there occur any superposition of contiguous or neighboring tubes 3'.

Thus, with the close-fitting arrangement of the tubes 3' over their entire length, the shape of the cross sections $3q'$ of these tubes constitutes a characteristic tube parameter, being determined in any plane E' (FIG. 2) orthogonal or perpendicular to the duct's axis A_4' , by the size of the cross-sectional area $4q'$ of the duct in said plane E'.

In the region represented by reference character D and designating the largest cross-sectional area of the duct 4', all tubes 3' will have a circular cross section $3q'$, which will be gradually flattened the nearer the tubes come to lie to the duct's axis A_4' , such being in direct dependence upon the size of the respective cross-sectional area $4q'$.

FIG. 5 depicts in an enlarged scale the cross section $3q'$ of such a flattened tube 3' as such occurs in the narrowest part of the duct 4', that is in the plane E' with the smallest cross-sectional area $4q'$ (cf. section-lines IV-IV and V-V in FIG. 2). The contour of the tube's cross section is angularly flattened towards the duct's axis, as is visualized by the two tangential lines marked T. For further illustration and comparison, the original circular cross section of the tube 3' is represented in dotted lines.

As in the case of the embodiment according to FIG. 1, here too, the tubes 3' are surrounded by a gas-tight casing 5 which

follows the longitudinal profile of the duct 4' and once again, the tubes 3' may be provided on their inner face with studs or the like and a layer of refractory material for protection of such tubes against excessive thermal load.

5 Furthermore, also as in the case of FIG. 1, here too, instead of the tubes 3' being arranged in close fit, side-by-side, that is, without any spacing or intervals therebetween, any desired spacing between them may be adopted. Similarly, instead of a circular cross section $4q'$, any other cross-sectional shape may be adopted for the duct 4'. However, here again, ducts of circular cross section are preferable, since, not only are the tubes 3' of identical shape and length, but, besides, an even distribution of the thermal load is ensured.

10 The embodiment of the invention described above in conjunction with FIGS. 2 to 5 is particularly suited for lengthwise extending heat exchange assemblies.

15 In the two embodiments of heat exchange assembly, as previously considered with regard to FIG. 1 and FIGS. 2-5, respectively, the tubes 3 and 3', respectively, serve as boiler tubes with a high thermal load. In consideration of this, it is recommended that they are located in close-fitting side-by-side arrangement, that is to say, without intervals or with small intervals or spacing of not more than a few millimeters. At 20 lower thermal loads, however, it is obvious that the tubes may be spaced from each other, that is, arranged with greater spacing or intervals, thus embracing a greater periphery with the same number of tubes. In both embodiments, spaced arrangements may be adopted, with equal spacing over the entire 25 length of the tubes or varying in width.

30 In conclusion, it may be emphasized that the two principle embodiments of heat exchange assemblies as described above and by way of example, may very easily be adapted to comply with any requirements.

35 FIG. 6 represents a heat exchange assembly with two ranges or rows of tubes R_1 and R_2 which are coaxially arranged in a duct 4'' having the longitudinal axis A'' . These tubes R_1 and R_2 have their ends connected to two headers 1 and 2. The external row or range R_1 of the tubes 3'' defining the duct 4'' proper, is in principle shaped and arranged as in the embodiment according to FIGS. 2-5, with however, wider intervals between the tubes, said intervals being equal for all tubes 3''. The tubes 3i of the inner row or range R_2 , placed coaxially within the duct 4'' and defining a second, inner duct 4i'', are 40 similarly shaped and arranged, with equal intervals of larger width, e.g. 100 millimeters for all tubes 3i, to thereby allow the upward stream of hot, heat-transmitting gases to flow (as indicated by the arrows P) towards the outer range of tubes R_1 . In this range R_1 the intervals or spacing of the tubes are 45 much smaller, with some 20 millimeters as an average. With intense heat transmission by radiation, the tubes 3'' in the outer range R_1 are still more closely arranged. Both rows or ranges R_1 and R_2 may have their tubes located in coinciding or displaced position with respect to each other.

50 55 The cross-sectional area $4q''$ of the duct 4'' is variable along the duct's axis A'' , but of circular shape throughout and so is the cross-sectional area $4qi$ of the inner duct 4i'' defined by the inner range or row of tubes R_2 . Thus, in this case too, the tubes 3'' of the outer range R_1 are all equal in length and shape and so are the tubes 3i of the inner range R_2 . The gas-tight casing 5 fits or encloses the contour of the outer tube range or row R_1 .

60 65 In FIG. 7 there is shown a further embodiment of the heat exchange assembly according to the present invention, with a duct marked 4_{hyp} having the shape of an hyperboloid of revolution, incorporating straight tubes 3g lying within the hyperboloid's surface, all tubes having the same shape and length.

70 75 It is well known that by rotation of an hyperbola around its vertical axis (y - y) a continuous surface of an hyperboloid of revolution (hereinafter briefly referred to as a hyperboloid) is being generated, with straight lines entirely lying within said surface, said straight lines being inclined with regard to the rotational axis (y - y).

On this mathematical property of the hyperboloid, the embodiment of the heat exchange assembly, represented in FIG. 7, is based. Here again, with the tubes 3g arranged close-fitting, side-by-side over their entire length, that is, without intervals, the direction of the tubes' axes constitutes a tube-parameter for all tubes 3g in any plane E_{hyp} , orthogonal to the axis A_4''' of the hyperboloidal duct 4_{hyp}, said tube parameter depending upon the size of the cross-sectional area 4_{hyp} in the respective plane E_{hyp} .

It is further known, that in the neck of the hyperboloid, that is in the narrowest part of the duct 4_{hyp}, the distance between the axes of two contiguous tubes 3g, is a minimum. Beginning from this narrowest part of the duct 4_{hyp}, the distance between two contiguous tubes is increasing in a linear, i.e. continuous way, to reach a maximum at the upper and lower ends of the hyperboloid. With hyperboloids of slender profile, i.e. with a less pronounced neck, as is the case in practice, the deviation in distance along the entire length of the duct 4_{hyp} is very small, so that the tubes 3g may be considered as being at equal distances. Furthermore, since the duct 4_{hyp} is of circular cross section in any sectional plane E_{hyp} along its entire length, equal thermal load for all tubes 3g is ensured.

At high thermal loads, the tubes have to be arranged in close fit side-by-side, as already mentioned, in other words with no spacing or intervals or with very small intervals of a few millimeters. The embodiment with the hyperboloid-shaped duct 4_{hyp} fulfills this requirement, since in the neck of the duct, i.e. in the place of highest heat concentration, the distance between contiguous tubes is minimum.

Considering furthermore, that the inclination of the straight tubes 3g may be chosen either to the left or to the right, i.e. corresponding or opposed to the spin of the gas-stream issuing from the furnace, thereby increasing or reducing the initial turbulence of the gas-stream, it is obvious that the embodiment with hyperboloid-shaped duct, is adaptable to requirements as may arise in practice.

It will be noted that in the case of the embodiment according to the FIG. 7, the basic longitudinal profile of the duct 4_{hyp} is predetermined by the hyperbola generating the hyperboloid in contrast to the embodiments according to FIG. 1, FIGS. 2-5 and FIG. 6, where any desired longitudinal profile is possible. However, the hyperboloidal-shaped duct is not only easily adaptable to all thermal and aerodynamical requirement, but moreover, this embodiment is advantageous in that, for ducts with variable cross section along their axes, straight tubes 3g of equal length may be used and arranged in close-fitting position over their entire length. Thus, expensive labor for the curved shaping of the tubes may be spared.

Instead of a single row or range of tubes 3g as illustrated in FIG. 7, two or more ranges can be arranged coaxially within the hyperboloid-shaped duct 4_{hyp}, in the manner already described in connection with FIG. 6.

As an alternative to the embodiments described above with the heat-transmitting fluid flowing through the duct, the position could be reversed by directing such fluid to flow through the tubes proper, with the heat-absorbing fluid then flowing in this case through the duct.

In conclusion, the versatility of the heat exchange assembly according to the invention should be emphasized.

While there is shown and described present preferred embodiments of the invention, it is to be distinctly understood that the invention is not limited thereto, but may be variously embodied and practiced within the scope of the following claims.

I claim:

1. A tubular heat exchange apparatus adapted to convey combustion gases from a furnace or the like, especially for heat transmission by radiation, comprising wall means defining a gas-tight casing, a plurality of tubes located within said gas-tight casing and in contiguous relation with said wall means, an inlet header and an outlet header at opposite ends of said casing, said plurality of tubes being operatively connected with said headers, said tubes being arranged adjacent one another throughout their entire length and defining a central duct of variable cross section, said tubes having their lengthwise axes curved in accordance with the longitudinal profile of said duct and disposed in axial planes of said duct, and the circumferential cross-sectional shape of said tubes, varying as a function of their distance from the longitudinal axis of said duct, substantially angularly flattened toward the ducts axis in that portion of said duct wherein said tubes are closest to said longitudinal axis, whereby with high gas velocities in chambers of intense radiation the free flow of the combustion gases is not hindered.

2. A heat exchange assembly as defined in claim 1, wherein said duct is of substantially circular cross section along its entire length and wherein said tubes possess equal length and shape.

3. A tubular heat exchange assembly as claimed in claim 2 and further including another plurality of tubes connected to said headers and arranged about said plurality of tubes, said another plurality of tubes being spaced from one another so as to provide flow passages for a heat exchange medium, both pluralities of tubes being arranged substantially coaxially with respect to the longitudinal axis of said duct.
